UNITED STATES PATENT OFFICE.

THOMAS MATSON, OF CHICAGO, ILLINOIS.

COMBINED CHINA CABINET AND REFRIGERATOR.

Application filed April 4, 1923. Serial No. 629,836.

To all whom it may concern:

Be it known that I, THOMAS MATSON, a citizen of Finland, residing at Chicago, in the county of Cook and State of Illinois, have invented certain new and useful Improvements in Combined China Cabinets and Refrigerators, of which the following is a specification, reference being had to the accompanying drawings, and to the reference characters marked thereon, which form a part of this specification.

This invention relates to a china closet and refrigerator combined in a unitary structure.

Many modern dwellings have apartments of one, two and three rooms. In such, the question of space for necessary furniture is most important. The principal object of my invention, therefore, is to produce as an article of household furniture, a cabinet which may be used for various purposes and occupy a minimum of floor space.

A refrigerator is an unsightly and undesirable article of furniture to be placed in a dining room, and a china and glassware cabinet is inappropriate in the kitchen. Another object of my invention is to produce a combined refrigerator and china and glassware cabinet, in one article of furniture, of such size and pleasing appearance as to make it suitable for use in either a kitchen or dining room.

These and other objects and advantages of my invention will be manifest as I proceed with my specification.

My invention consists in the device herein illustrated, described and more particularly pointed out in the appended claims.

In said drawings:

Fig. 1 is an elevation, in perspective, of a cabinet constructed in accordance with my invention.

Fig. 2 is an end view of the same.

Fig. 3 is a vertical, longitudinal sectional view, of the same, the section being taken in the plane indicated by the dotted line 3-3 of Fig. 2.

Figs. 4 and 5 are vertical, transverse, sectional views, enlarged, of portions of the cabinet, the sections being taken in the planes indicated by the dotted lines 4-4 and 5-5, respectively, of Fig. 3.

The cabinet, indicated as a whole by A, comprises a back 1, two end members 2, 3, a bottom 4, top 5, and a front frame member 6. The compartment, B, is closed by a

glass door 7, secured to the front frame 6, and another compartment C, is closed by a glass door 8 secured in the front frame 9. A cooling compartment D extends vertically along the side of the compartment B, while the compartment C is above and extends practically across the top of the compartments B and D.

A plurality of shelves 10 may be placed in the compartment B, which is designed to hold china and glassware, and there is, preferably, one shelf 11 positioned in the compartment C.

The compartment D is divided into an upper section or ice chamber 12 and a lower section 13, by a horizontal partition 14. A hinged door 15 affords means of access to the ice chamber 12 at the end of the cabinet and a panel, hinged door 16 affords means of access to the same compartment from the front. A hinged door 17 affords means of access to the lower compartment 13, from the front.

The ice chamber 12 is provided with a suitable lining 17, after the manner of refrigerator boxes, and between this lining and the adjacent walls of the cabinet is a suitable insulating material 18. That part of the lining 17 which rests upon the partition 14, has a flanged aperture 19 which surrounds and registers with an opening 20 in the partition 14, thereby permitting cool air to descend from the ice chamber 12 to the chamber 13 beneath it. An ice rack 21 is provided for the chamber 12 to suitably support a cake of ice, indicated by the dotted line 22.

Attached to the upper wall in the ice chamber 12 is a link 23, its lower end having pivotal engagement with a woven wire shelf 24. The other end of said shelf 24 rests upon a bracket 25, on the vertical wall of the lining 17. This affords convenient means for supporting some special articles such as butter, cream, etc., in close proximity to the ice in the compartment. When not in use, as for example, when the ice chamber is completely filled with ice, this shelf 24 will be supported from the ceiling, one end engaging the bracket hook 26 and the other end being locked in its raised position by the latch 27 pivotally mounted on the upper wall. In the lower cool chamber 13 is a woven wire shelf 28 suitably supported on brackets 29.

The drip water from the melting ice in

the chamber 12 will be passed off through a drain pipe 30, which is connected at its upper end through the wall 14 with the ice chamber 12 and at its lower end through the bottom wall 4 to a water receptacle 31. The cabinet A, as a whole, is mounted upon supports, preferably castors 32, which extend a slight distance below the bottom 4. This affords a space or compartment E in which I place two sliding drawers 33 and 34, the former being beneath the discharge end of the drain pipe 30 and the latter being beneath the compartment 13. Hinged doors 35 and 36 in the front of the cabinet afford convenient means of access to the compartment E, so that said drawers 33 and 34 may be removed therefrom as occasion may require.

The drawers 33, 34, are metal lined and near the upper edge of one side wall of the drawer 33 is an overflow aperture 37 which is in communication with a stationary conveyor or trough 38, leading into the drawer 34. It frequently happens that the housewife or person attending to such duties will neglect to empty the receptacle containing the drip water from the refrigerator, and in order, therefore, to prevent the water in the drawer 33 from overflowing its upper margins and flooding the floor of the room in which the cabinet is placed, it will be understood that the water will drain off into the second receptacle, to-wit: the metal lined drawer 34.

From the foregoing description it will be manifest that a small family, living in a one, two or three room apartment, where space is valuable, may thus have in one article of furniture, an ornamental cabinet in which china and glassware may be conveniently placed and which will not have the objectionable appearance of a refrigerator or ice box, and which at the same time will have a refrigerating compartment D in which a fair quantity of ice may be placed in the upper chamber, and in which the easily perishable articles of food may be stored in a lower chamber; and, further-

more, in which the probability of carelessness in the handling of the drip water from the refrigerator will be neutralized by the ample provision made for such drip water.

I claim as my invention:

1. As a new article of manufacture, the combined china cabinet and refrigerator having a two chamber refrigerating compartment, a vertically arranged china compartment, laterally disposed with respect to the refrigerator compartment, and an upper china compartment extending over the first mentioned china compartment and the refrigerator compartment, a shallow lower compartment extending the width of the cabinet and provided with two removable receptacles, a water conduit from the refrigerator compartment leading to one of the receptacles and an overflow pipe leading from one receptacle to the other.

2. As a new article of manufacture, the combined china cabinet and refrigerator having a two chamber refrigerating compartment, a vertically arranged china compartment, laterally disposed with respect to the refrigerator compartment, and an upper china compartment extending over the first mentioned china compartment and the refrigerator compartment, a shallow lower compartment extending the width of the cabinet and provided with two removable receptacles, a water conduit from the refrigerator compartment leading to one of the receptacles, an overflow pipe leading from one receptacle to the other, a woven wire shelf in the ice chamber of the refrigerator compartment and means for securing the same when not in use to the ceiling of the ice chamber, said securing means embracing a fixed bracket and a pivoted latch.

In testimony, that I claim the foregoing as my invention I affix my signature, in the presence of two witnesses, this 3rd day of April, 1923.

THOMAS MATSON.
